UNITED STATES PATENT OFFICE

FORREST ADDITON, OF FLOWERY BRANCH, GEORGIA

WARNING SIGNAL

Application filed May 16, 1930. Serial No. 452,993.

This invention relates to a warning signal particularly adapted to be carried by wagons and the like, and has for its primary objects to provide, in a manner as hereinafter set forth, a warning signal of such class by means of which the light rays from an approaching automobile will be reflected to instantly warn the operator of the automobile of the proximity of the wagon or the like whereby the likelihood of a collision will be eliminated.

A further object of the invention is to provide a warning signal of the character aforesaid which includes a multi-bladed element mounted in a manner to cause the rotation thereof by the slightest breeze, the blades of the element alternately presenting highly polished and brightly colored surfaces for reflecting and coloring the light rays from an approaching automobile.

With the foregoing and other objects in view, the invention consists of the novel construction, combination and arrangement of parts as illustrated in the accompanying drawing wherein are shown several embodiments of the invention, and as hereinafter more particularly described, but it is to be understood that the drawing and description are to be taken as illustrative and that the invention is intended to be limited only by the scope of the claims hereunto appended.

In the accompanying drawing in which like numerals are employed to designate like parts throughout the several views:—

Figure 1 is a perspective view of a warning signal in accordance with this invention.

Figures 2, 3, 5 and 6 are similar views respectively illustrating modified forms of the invention.

Figure 4 is an elevation illustrating a further modified form of the invention.

Figure 7 is a sectional elevation illustrating the manner of mounting the rotatable light reflecting elements of the several forms shown, and further illustrating the shape of the light reflecting blades in the form shown in Figure 4.

Referring to the drawing in detail, the numeral 1 indicates a supporting post which is adapted to have its lower end connected in any suitable manner to a wagon or the like

in connection with which the warning signal is to be used. By way of example, I show attached to the lower end of the post 1 a clip 2 which includes a pair of spaced clamping fingers 3.

Rotatably mounted on the upper end of the post 1, and extending in alignment therewith, is a stem 4 upon which is mounted a plurality of radially projecting blades 5 and 6. The blades 5 are alternately arranged with respect to the blades 6 and are highly polished on their side faces as indicated at 7. The blades 6 have their side faces brightly colored as indicated at 8, such colored faces preferably being red as shown. The blades 5 and 6 are of elongated rectangular formation.

In the form of the invention shown in Figure 2, the stem 4 is provided with a plurality of radially projecting blades 9 which are of the same shape as the blades 5 and 6 shown in Figure 1. Each of the blades 9 is highly polished on one side face thereof as indicated at 10, and is brightly colored on the opposite side face thereof as indicated at 11. Preferably the color of the side faces 11 is red.

In the form of the invention shown in Figure 3, the stem 4 is provided with a plurality of radially projecting blades 12 and 13 which are alternately arranged in the same manner as the blades 5 and 6 described in connection with Figure 1. The side faces of the blades 12 are highly polished as indicated at 14, while the side faces of the blades 13 are brightly colored as indicated at 15. The upper edge faces of the blades 12 and 13 are downwardly and outwardly inclined whereby the blades gradually decrease in height in an outer direction.

In the form of the invention shown in Figure 4, the stem 4 is provided with a plurality of alternately arranged blades 16 and 17. The side faces of the blades 16 are highly polished as indicated at 18, while the side faces of the blades 17 are brightly colored as indicated at 19. The blades 16 and 17 are substantially of semi-circular shape as clearly illustrated in Figure 7.

In the form of the invention shown in

Figure 5, the stem 4 has mounted thereon a thin reflecting element of unitary construction indicated generally by the numeral 20. The element 20 is inwardly crimped on opposite sides thereof to provide a plurality of radially extending ridges 22 on the upper face of the element, and a plurality of downwardly and outwardly inclined ridges 21 on the lower face of the element. The entire lower face of the element 20 is highly polished as indicated at 24. The portions of the upper face of the element 20 merging into alternating ridges 21 are brightly colored as indicated at 23, while the remaining portions 25 of the upper face are highly polished as indicated at 25, the portions 25 being alternately disposed with respect to the portions 23.

In the form of the invention shown in Figure 6, the stem 4 is provided with a plurality of alternately arranged, radially projecting blades 27 and 28. The side faces of the blades 27 are highly polished as indicated at 29, while the side faces of the blades 28 are brightly colored as indicated at 30. The lower edge faces of the blades 27 and 28 are inclined inwardly and upwardly whereby the blades gradually decrease in height in an inward direction.

As illustrated in Figure 7, the stem 4 employed in connection with each of the forms shown is provided with a socket 31 opening through the lower end of the stem. Formed on the upper end of the post 1 is a concentrically arranged needle 32 which is formed with a tapered upper end 33 extending into a correspondingly tapered recess in the upper wall of the socket 31.

In the use of the device, the post 1 is secured to a wagon or the like, and upon the subjection of the device to a slight breeze, such as by movement of the wagon, the reflecting element mounted on the post 1 will be rotated, and upon the light rays of an approaching automobile striking the rotating element, the light rays will be thrown alternately upon highly polished surfaces and brightly colored surfaces whereby the light rays will be colored and reflected substantially in a simulation of a series of successive blinks, thereby instantly attracting the attention of the operator of the vehicle and warning the operator of the proximity of the wagon or the like while still too far distant to readily see the latter.

It is thought that the many advantages of a warning signal in accordance with this invention will be readily apparent, and although the signal preferably will be constructed in accordance with the embodiment herein shown and described, it is to be understood that various changes in the details of construction may be resorted to, so long as such changes fall within the scope of the invention as defined in the appended claims.

What I claim is:

1. In a warning signal, a rotatable stem, and a plurality of blade elements projecting radially from the stem, said blade elements alternately presenting highly polished and brightly colored surfaces.

2. In a warning signal, an elongated support, a stem rotatably mounted on the upper end of the support, and a plurality of blade elements projecting radially from the stem, said blade elements alternately presenting highly polished and brightly colored surfaces.

3. In a warning signal, an elongated support, a needle projecting from the upper end of the support, a stem formed with a socket for receiving said needle to rotatably mount the stem, and a plurality of blade elements projecting radially from the stem, said blade elements alternately presenting highly polished and brightly colored surfaces.

4. In a warning signal, an elongated support, a stem rotatably mounted on the upper end of the support, a plurality of blade elements projecting radially from the stem, said blade elements alternately presenting highly polished and brightly colored surfaces, and means for detachably securing the lower end of the support to an object.

In testimony whereof, I affix my signature hereto.
